UNITED STATES PATENT OFFICE

JOSEPH BERGER, OF UTICA, NEW YORK, ASSIGNOR TO UNION SPECIAL MACHINE COMPANY, OF CHICAGO, ILLINOIS, A CORPORATION OF ILLINOIS

FEEDING MECHANISM FOR SEWING MACHINES

Application filed May 10, 1938. Serial No. 276,783.

The invention relates to new and useful improvements in feeding mechanisms for sewing machines, and more particularly to a feeding mechanism for a sewing machine having a cylindrical work supporting arm for feeding the material lengthwise of the arm as it is stitched.

An object of the invention is to provide a feeding mechanism wherein the feed dog is moved back and forth by a direct thrust on the feed bar centrally thereof.

A further object of the invention is to provide a feeding mechanism for sewing machines of the above type wherein the actuating parts are so positioned relative to each other as to reduce the lateral dimensions of the feeding mechanism to a minimum so that the arm of the machine may be relatively small.

These and other objects will in part be obvious and will in part be hereinafter more fully disclosed.

In the drawings which show by way of illustration one embodiment of the invention:

Figure 1 is a view partly in front elevation and partly in vertical section of a machine embodying the improvements.

Fig. 2 is a sectional view through the work supporting arm showing the feeding mechanism therein in plan, the looper and spreader mechanism being omitted.

Fig. 3 is a sectional view on the line 3—3 of Fig. 2.

The feeding mechanism embodying the invention is particularly adapted for a sewing machine having a work supporting arm along which the material is fed while it is being stitched. The material is preferably fed off the end of the arm. In order to accomplish this the feeding mechanism includes a feed dog which has four motions and during its feeding motion it moves in a direction lengthwise of the arm and toward the free end of the arm. The feed dog is carried by a feed bar which extends longitudinally of the arm to a point adjacent the depending member on which the arm is suspended. The feed dog is raised and lowered by means of a lever connected by links

to the feed bar adjacent the forward end thereof.

This lever is oscillated by an eccentric strap cooperating with an eccentric on the main shaft which in the present type of machine is disposed in the upper frame of the machine. The feed bar is moved back and forth by a rocking frame which is oscillated by a rock shaft, and the rock shaft, in turn, is oscillated by an eccentric strap cooperating with an eccentric on the main shaft. The novel features of the invention are particularly found in the construction of the feed bar and the arrangement of the rocking frame and the connection thereof to the feed bar. The feed bar has a raised bridging portion adjacent its rear end and the rocking frame is provided with an adjustable stud extending underneath this bridging portion. This stud is mounted in a slot so that it can be shifted for varying the stroke imparted to the feed bar. A link connects the stud to a forked portion in the feed bar well beyond the longitudinal center of the feed bar. The link is so disposed as to lie substantially in a vertical plane containing the longitudinal center axis of the feed bar.

Referring more in detail to the drawings:

The invention is shown as applied to a sewing machine having a supporting base 1 on which is mounted an overhanging bracket 2 carrying a frame 3 at its upper outer end. Mounted in said frame is a main shaft 4. At one end of this frame is a forwardly projecting housing carrying a needle bar 5 which is provided with two needles 6, 6. At the other end of the frame is a depending member 7. At the lower end of the depending member is a work supporting arm 8 which is suspended thereby. The work supporting arm is so disposed that the needles operate at the free end of the arm. Cooperating with the needles beneath the work support are loopers 9, 9, one for each needle, and cooperating with the loopers is a loop spreader 10.

The mechanism for operating the loopers and the mechanism for operating the spreader form no part of the present invention, but are shown described and claimed

in my copending application, Serial Number 275,068, filed May 4, 1929.

The material is fed lengthwise of the work supporting arm by a feed dog 11. The feed dog 11 is carried by a feed bar 12. The feed bar 12 extends lengthwise of the work supporting arm and lies in a vertical plane substantially centrally of the work supporting arm. Said feed bar is mounted adjacent the feed dog on supporting links 13 which in turn are mounted on a lever 14 pivoted at 15. The lever 14 is oscillated by means of an eccentric strap 16 which cooperates with an eccentric 17 on the main shaft 4. The main shaft 4 extends lengthwise of the upper frame and actuates devices at one end thereof for reciprocating the needle bar, and also actuates devices at the other end thereof for operating the looper and spreader.

The feed bar at the rear end thereof is forked as indicated at 19. This forked end of the feed bar straddles a pin 20. The pin 20 is journalled in a rocking frame 21. This rocking frame is mounted for oscillation on a supporting rod 22. This rocking frame is provided with a segmental slot 23 in which is mounted a stud 24. The stud is capable of being adjusted in the slot and secured in adjusted positions. A link 25 engages the stud 24 at one end and the other end of this link extends between the forks 26, 27 formed in the feed bar. A pivot pin 28 secures the link to this portion of the feed bar. When the rocking frame is oscillated back and forth the link will impart an endwise thrust for moving the feed dog for feeding the material and this endwise thrust on the feed bar is applied to the feed bar substantially at the center line of the feed bar.

This avoids lateral strain and cramping of the feed bar as it moves back and forth. The feed bar is guided in its back and forth movements by bearing blocks 29, 29 carried by the arm. This direct thrust reduces to a minimum the wear on the guide blocks and insures that the feed dog will move uniformly in the same path during the stitching of the fabrics.

The rocking frame 21 is oscillated by means of a link 30 which is connected to a stud carried by the rocking frame at one end and to a stud carried by an arm 31 mounted on a sleeve 32, which, in turn, is mounted for free oscillation on a shaft 33. The sleeve carries a second arm 34 provided with a ball stud 35 with which an eccentric strap 36 cooperates. This eccentric strap engages an eccentric 37 on the main shaft 4.

From the above it will be apparent that I have provided a feeding mechanism wherein the parts for moving the feed bar back and forth and raising and lowering

the same occupy a very small space in a lateral direction and thus the arm of the machine may be made comparatively small in size. Furthermore, I have provided a feeding mechanism wherein the thrust of the actuated parts are substantially in a line. It will be noted that the link 25 is substantially in line with the feed bar, being disposed substantially centrally of the line of feed, and this contributes to a feeding mechanism wherein the machine may be operated at a very high speed with very little vibration of the parts.

It is obvious that minor changes in the details of construction and the arrangement of the parts may be made without departing from the spirit of the invention as set forth in the appended claims.

Having fully described my invention, what I claim as new and desire to secure by Letters Patent, is:

1. A feeding mechanism for sewing machines comprising a feed bar, a feed dog carried at one end thereby, means for slidably supporting the other end of the feed bar, means for raising and lowering the end of the feed bar carrying the feed dog, and means for moving said feed bar endwise including a link pivoted to the feed bar intermediate its ends and lying in a vertical plane substantially coincident with the line of feed.

2. A feeding mechanism for sewing machines comprising a feed bar, a feed dog carried at one end of said feed bar, a swinging frame for slidably supporting the other end of said feed bar, means for raising and lowering the end of the feed bar carrying the feed dog, and means for moving said feed bar endwise including a link connected at one end to said swinging frame at a point substantially beneath the feed bar and connected at its other end to said feed bar, said link lying substantially in a vertical plane coincident with the line of feed.

3. A feeding mechanism for sewing machines comprising a feed bar, a feed dog carried at one end of said feed bar, a swinging frame at the other end of said feed bar supporting a fulcrum pin, said feed bar having its end forked and slidably engaging said fulcrum pin, means connected to the feed bar for raising and lowering the end thereof carrying the feed dog, a link shiftably connected at one end to said swinging frame substantially beneath the feed bar and connected at the other end to the feed bar, said link lying substantially in a vertical plane coincident with the line of feed.

4. A feeding mechanism for sewing machines comprising a feed bar, a feed dog carried at one end of said feed bar, a swinging frame at the other end of said feed bar supporting a fulcrum pin, said feed bar having its end forked and slidably engag-

ing said fulcrum pin, means connected to the feed bar for raising and lowering the end thereof carrying the feed dog, a link shiftably connected at one end to said swinging frame substantially beneath the feed bar and connected at the other end to the feed bar, said link lying substantially in a vertical plane coincident with the line of feed, said feed bar having a forked portion between which the ends of the link extend and a pin passing through the forked portion and through the link.

5. A feeding mechanism for sewing machines comprising a feed bar, a feed dog carried at one end of said feed bar, a swinging frame at the other end of said feed bar supporting a fulcrum pin, said feed bar having its end forked and slidingly engaging said fulcrum pin, means connected to the feed bar for raising and lowering the end thereof carrying the feed dog, a link shiftably connected at one end to said swinging frame substantially beneath the feed bar and connected at the other end to the feed bar, said link lying substantially in a vertical plane coincident with the line of feed, said feed bar having an upwardly curved bridging portion extending over the connection with the swinging frame.

6. A feeding mechanism for sewing machines comprising a feed bar, a feed dog carried at one end of said feed bar, a swinging frame at the other end of said feed bar supporting a fulcrum pin, said feed bar having its end forked and slidingly engaging said fulcrum pin, means connected to the feed bar for raising and lowering the end thereof carrying the feed dog, a link shiftably connected at one end to said swinging frame substantially beneath the feed bar and connected at the other end to the feed bar, said link lying substantially in a vertical plane coincident with the line of feed, said feed bar having a forked portion between which the ends of the link extend and a pin passing through the forked portion and through the link, said feed bar having an upwardly curved bridging portion extending over the link connection with the swinging frame.

7. In a sewing machine the combination of a cylindrical work supporting arm, a feed bar extending lengthwise thereof, and carrying a feed dog at its outer free end, means connected to the feed bar for raising and lowering the end carrying the feed dog, a swinging frame mounted in said work supporting arm with which the inner end of the feed bar has a sliding fulcrum engagement, a link located beneath the feed bar and connected at one end to said swinging frame, said link being connected at its other end to the feed bar and lying substantially in a vertical plane coincident with the line of feed.

8. In a sewing machine the combination of a cylindrical work supporting arm, a feed bar extending lengthwise thereof, and carrying a feed dog at its outer free end, means connected to the feed bar for raising and lowering the end carrying the feed dog, a swinging frame mounted in said work supporting arm with which the inner end of the feed bar has a sliding fulcrum engagement, a link located beneath the feed bar and connected at one end to said swinging frame, said link being connected at its other end to the feed bar and lying substantially in a vertical plane coincident with the line of feed, said feed bar having an upwardly curved bridging portion extending over the connection between the link and the swinging frame.

9. In a sewing machine the combination of a cylindrical work supporting arm, a feed bar extending lengthwise thereof, and carrying a feed dog at its outer free end, means connected to the feed bar for raising and lowering the end carrying the feed dog, a swinging frame mounted in said work supporting arm with which the inner end of the feed bar has a sliding fulcrum engagement, a link located beneath the feed bar and connected at one end to said swinging frame, said link being connected at its other end to the feed bar and lying substantially in a vertical plane coincident with the line of feed, said feed bar having an upwardly curved bridging portion extending over the connection between the link and the swinging frame, said feed bar having a forked portion to receive the end of the link and a pin passing through the forked portion for joining the link to the feed bar.

In testimony whereof, I affix my signature.

JOSEPH BERGER.
